PORTABLE ICE SKATING FLOOR

Herman Vetter, Los Angeles, Calif.

Application May 2, 1947, Serial No. 745,470

9 Claims. (Cl. 62—12)

1

This invention relates generally to ice skating rink construction, particularly the type of construction having a hollow floor through which brine or a suitable fluid refrigerant is circulated for freezing a sheet of water supported on top of the floor.

It is an object of the invention to provide a new and improved rink construction of great flexibility embodying floor sections and other units adapted to be quickly set up and assembled to meet the requirements of size and shape of a particular installation site. It is also an object to provide an ice rink construction embodying a plurality of interchangeable hollow floor sections which are individually adapted to be detachably secured to each other or to a conduit supplying refrigerant.

It is a further object to provide a construction which can be readily dismantled into conveniently portable sections suitable for transportation to a new site. In this connection, it is an object to provide floor sections which are made up in such a manner that they may be easily racked or stacked on a truck or railway car.

Another object of the invention is to provide a means for resiliently holding the floor sections together as a unit while permitting them to expand and contract in the plane of the floor.

It is also an object of the invention to provide a floor type rink construction wherein means are provided for forming an improved indirect circulation path for the refrigerant through the floor and the individual sections of the floor.

It is a still further object of the invention to provide an improved means for supporting the floor sections.

These and other objects will be apparent from the drawings, which are merely for illustrative purposes. Referring to the drawings:

Fig. 1 is a schematic plan view of an ice skating rink embodying the invention;

Fig. 2 is an enlarged fragmentary plan view of one corner section of the rink shown in Fig. 1, the section being partly broken away;

Fig. 3 is a fragmentary section on line 3—3 of Fig. 2;

Fig. 4 is a fragmentary section on line 4—4 of Fig. 2;

Fig. 5 is an enlarged fragmentary sectional plan of the coupling means for the fluid conduit at one end of the section;

Fig. 6 is an enlarged fragmentary sectional plan of the ends of two adjacent floor sections showing the connecting means therefor;

Fig. 7 is a section on line 7—7 of Fig. 2;

2

Fig. 8 is a fragmentary section on line 8—8 of Fig. 2; and

Fig. 9 is an enlarged detail section showing the means securing a cross beam to a floor section.

More particularly describing the invention, referring to Fig. 1, reference numeral 11 generally indicates an ice skating rink floor which is formed of a plurality of sections 12. Any number of such sections may be used and, as later will become apparent, the sections are adapted to be detachably joined at their ends and the sections at the side of the rink connected to branch conduits 14 leading from a main conduit. Reference numeral 15 indicates a main supply pipe or supply conduit and reference numeral 16 a main return pipe or conduit.

Preferably the floor as a whole is bounded by a curb 18 and a plurality of resilient curb holders 20 provided at spaced points around the curb for yieldably urging the curb against the sections making up the floor.

Referring now to Figs. 2—9 inclusive for a more detailed description of the construction, each of the sections 12 includes a top or floor plate 22 upon which the sheet of ice is supported. Below the floor plate is a bottom plate 23 which cooperates with the top plate and suitable side walls 24, 24' to form a substantially elongated rectangular space or chamber 25 between the two plates for the circulation of refrigerant. At each end of the section there is provided a header or header box 26 which depends from the floor section and includes the end wall 27, inner wall 28 and bottom wall 29. The bottom plate 23 forms the upper wall of the header and in the form of the invention shown in Figs. 2—9, the plate is provided with a pair of openings 30 and 30', one at each end of the section providing communication between the chamber 25 and the headers for the passage of brine. Hereinafter the word "brine" will be used in the sense that it includes any suitable fluid refrigerant which could be forced through the floor sections and the rink as a whole.

Preferably the sections are provided with one or more partition walls to control the path taken by the brine in passing from the opening 30 at one end to the opening 30' at the other, and in one form of the invention, the two partitions 32 and 33 are shown (Fig. 2). The partition 32 extends from the outer wall at one end of the section to a point spaced from the opposite end of the section, leaving an opening 34. The other partition extends inwardly from said opposite end of the section to a point spaced from the other

end wall, leaving an opening 35. With this construction, assuming that the brine enters the header nearest supply pipe 15 (Fig. 2), it will pass upwardly into the floor space 25 through the opening 30 and through the passageway defined by the outer wall of the section and the partition 32, around the end of the partition through opening 34, and return through the center passageway defined by the two partitions, pass around partition 33 through opening 35 and flow to and through opening 30' at the opposite end of the section.

Each section at its end is provided with an opening 36 disposed centrally of the end wall 27 for the passage of brine. Preferably this opening is defined by an inwardly curved lip 37 (Figs. 5 and 6) providing an annular recess 38. Extending through the header at each end, one on each side of the opening 36, is a pair of tubes 40 which receive bolts 41 for the purpose of securing adjacent sections (Fig. 6) or for securing a flanged fitting 43 (Fig. 5) to which a brine conduit may be attached. Preferably a resilient sealing ring 44 is provided between the lip portions 37 of the adjoining sections (Fig. 6) and between a section and the fitting 43 (Fig. 5) which is provided with an annular recess 45 to accommodate the ring.

It will be apparent that with this construction any section may be bolted to an adjoining section at one end or both ends or it may be attached at either or both ends to a brine conduit. Any suitable conduit means may be provided between the section and the main conduits, such for example as the hose 46 mounted on the fitting 43 at one end and on a pipe section 47 of the main pipe 15.

For the purpose of facilitating assembly of the sections and the mounting of them, each section is provided with a pair of supporting skids or cross beams 50 which are rigidly attached to the section and correspond in length to the width of the section. In Fig. 9 there is shown a means for attaching the beams which includes a bolt 51, the head of which is recessed in the floor and abuts an insert washer 52 which is welded in place between the upper and lower floor plates. The bolt extends through bore 53 in the beam and is provided with a nut 54 at its lower end which is received within a counterbore 55 in the beam.

When the sections are assembled they are joined together to form the desired configuration of the floor and the skids or cross beams 50 rest on main beams 58 which may extend the width of the floor or any desired length, the longitudinal axis of the beams being located in alignment with the side edges of adjoining sections so that the cross beams 50 of laterally adjacent sections will each be supported by the beam, extending to the center thereof, as shown in Fig. 2.

The rink as a whole is preferably provided with a curb 18 which may consist of a plurality of suitable timbers such as 2 x 4's 60 around the periphery of the rink. The curb is yieldably held against the ring by the several resilient curb holding means 20 heretofore referred to. This means in each case includes a bracket 62 (Fig. 4) which at the side of the rink is supported on and bolted to the main beams 58 at a point spaced outwardly of the curb. This bracket forms an abutment for a spring 63 which yieldably presses against a curb plate 64, abutting the curb and preferably extending under it,

as shown, the plate being L-shaped. Means may be provided for contracting the spring and relieving the pressure thereof from the curb when desired, and such means may take the form of a stem 65 threadedly mounted in a boss 66 on the plate. The stem extends through a hole in the bracket and is pivotally secured off center to a handle 68 which bears against the outer surface of the bracket. The handle may be pivoted from the position in which it is shown in Fig. 4 to the broken line position for the purpose of contracting the spring.

As indicated in Fig. 8, at the ends of the rink the brackets 62 are necessarily mounted on special cross beams 50' which in the case of the end sections are formed to provide an extension 70 for this purpose.

This construction serves to hold the curb in position around the periphery of the rink and to hold the rink floor sections together while allowing for expansion and contraction thereof in the plane of the floor.

In Fig. 10 there is shown another form of floor section which differs from the form previously described in the location and arrangement of the partitions for controlling the flow pattern of the brine through the section. Referring to that figure, reference numeral 75 indicates the section generally which is provided with a top plate 76, a bottom plate 77, and headers 78 at each end. Located between the top and bottom plates are a plurality of partition elements so arranged that each end of the section is identical to the other. A partition wall 80 extends longitudinally of the floor section in two sections 81 which are respectively adjacent the sides of the floor section and a middle section 82, the three longitudinally extending sections being connected at their ends by U-shaped portions or sections 83 which are spaced inwardly of the ends of the floor section. Additionally a pair of partition walls 85 are provided which respectively extend from the end wall inwardly to a point spaced from the U-shaped sections 83. At each end the bottom or lower plate 77 is apertured at 86 at diagonally opposed corners to provide communication between the floor space and the interior of the headers. With the construction shown it will be apparent that, assuming brine enters the lower header, it will leave the header through the opening 86 therein and flow toward the other end of the floor section and eventually reach the diagonally opposite opening 86 at the other end of the floor section and flow into the other header and out to the next adjoining section. In flowing from one end to the other the brine will follow the pattern indicated by the arrows on the figure and it will be apparent that it will twice reverse itself in passing through the floor section.

It will be apparent from the construction described that a rink construction has been provided which may be readily assembled at any site to meet the requirements as to size and shape necessitated by the site. It may also be quickly dismantled and moved to a new site. As previously pointed out, the individual floor sections 12 are provided with cross beams 50 which rest on longitudinally extending beams 58 and the entire floor, including the curb surrounding it, is held in place by the resilient curb holding means generally indicated by 20. It may be desirable to provide additional support for the floor and this may take the form, for example, of 2 x 4 timbers indicated at 90 (Fig. 3) secured

together at their ends (not shown). Instead of providing special cross beams on the floor sections at the ends of the rink for supporting the individual curb holding elements 20, such elements can be mounted on selected timbers 90.

It will be apparent that a highly flexible portable rink construction has been provided in which individual sections in any number may be bolted together to form a floor of desired size and shape. While the floor sections have been shown as rectangular since such shape is the most practical, it is contemplated that, where desired, sections having various shapes in plan may be used to produce special shaped rinks.

Although the invention has been particularly shown and described, it is contemplated that various changes and modifications can be made without departing from the scope of the invention as set forth in the claims.

I claim:

1. In ice rink construction, a plurality of hollow floor sections joined together in edge to edge relation constructed and arranged for circulation of a refrigerant therethrough, means forming a curb around said sections, and resilient means at spaced points along the outer side of said curb yieldably urging the curb against said sections.

2. In ice rink construction, a plurality of hollow floor sections joined together in edge to edge relation constructed and arranged for circulation of a refrigerant therethrough, supporting means for said floor sections including a plurality of spaced beams thereunder, means forming a curb around said sections, certain of said beams extending beyond said floor sections, means on the extended beams outwardly of said curb providing a plurality of abutments, and a spring means between each of said abutments and said curb for yieldably urging said curb against said floor sections.

3. In ice rink construction, a plurality of hollow floor sections joined together in edge to edge relation constructed and arranged for circulation of a refrigerant therethrough, means forming a curb around said floor sections, a plurality of abutments spaced around said curb outwardly thereof, spring means between said abutments and said curb yieldably urging said curb against said floor sections, and means for rendering said spring means inoperative.

4. A floor section adapted to form part of an ice rink construction comprising plate means defining an elongated rectangular flat shallow space through which a refrigerant can be circulated, and means forming a header box extending transversely of the section at each end thereof, said header boxes each having an opening at the end of the section, and an opening communicating with said space.

5. A hollow floor section adapted to form part of an ice rink construction comprising plate means defining an elongated rectangular flat shallow space through which a refrigerant can be circulated, and means forming an enclosed header box extending transversely of the section at each end thereof, said header boxes each having an exterior opening providing communication between the exterior of the floor section and the interior of the header box at the end of the section and an interior opening providing communication between the interior of said header box and the interior of said space, and partition means dividing said space into fluid passageways extend-

ing indirectly from the interior opening into one header box to the interior opening into the other.

6. A floor section adapted to form part of an ice rink comprising a rectangular floor plate, a bottom plate spaced a relatively short distance below said floor plate, side and end walls connecting said floor and bottom plates, and walls at each end of said section forming a header box extending transversely thereof and depending below said bottom plate, said header box having an opening in a wall thereof providing communication between the interior of the header box and the exterior of the floor section, said bottom plate having an opening into each of said headers.

15 7. A floor section adapted to form part of an ice rink comprising a rectangular floor plate, a bottom plate spaced a relatively short distance below said floor plate, side and end walls connecting said floor and bottom plates, walls at each 20 end of said section forming a header box extending transversely thereof and depending below said bottom plate, said header box having an opening providing communication between the interior of the header box and the exterior of the floor section, said bottom plate having an opening into each of said headers, and partition means between said plates providing an indirect flow passageway between the openings in said bottom plate communicating with said headers.

25 8. A floor section adapted to form part of an ice rink comprising a rectangular floor plate, a bottom plate spaced a relatively short distance below said floor plate, side and end walls connecting said floor and bottom plates, walls at each 30 end of said section forming a header box extending transversely thereof and depending below said bottom plate, said header box having an opening centrally disposed in the outer side thereof, and a pair of tubes extending through 35 each end of said section forming a header box extending transversely thereof and depending below said bottom plate, said header box having an opening centrally disposed in the outer side thereof, and a pair of tubes extending through 40 said header boxes one at each side of said opening, said tubes being adapted to receive bolts for attaching floor sections together, said bottom plate having an opening into each of said headers.

45 9. A floor section adapted to form part of an ice rink comprising a rectangular floor plate, a bottom plate spaced a relatively short distance below said floor plate, side and end walls connecting said floor and bottom plates, walls at each 50 end of said section forming a header box extending transversely thereof and depending below said bottom plate, said walls including a header end wall at the end of each section provided with a centrally disposed opening, said 55 header end wall being provided on its outer side with an annular recess surrounding the opening, said recess being adapted to receive a gasket, and a pair of tubes extending through said header boxes one at each side of said opening, said tubes being adapted to receive bolts for attaching floor sections together, said bottom plate having an opening into each of said headers.
